UNITED STATES PATENT OFFICE.

HENRY HUDSON, OF MALVERN, VICTORIA, AUSTRALIA.

INSERT FOR CONCRETE AND THE LIKE, TO RECEIVE NAILS AND OTHER FASTENERS,
OR BUILDING ELEMENTS.

1,348,801.

Specification of Letters Patent.

Patented Aug. 3, 1920.

Application filed June 11, 1918. Serial No. 239,472.

To all whom it may concern:

Be it known that I, HENRY HUDSON, a subject of the King of Great Britain and Ireland, etc., residing at Malvern, in the 5 State of Victoria, Commonwealth of Australia, have invented certain new and useful Improvements in Inserts for Concrete and the like, to Receive Nails and other Fasteners, or Building Elements, and I do 10 hereby declare the following to be a full, clear, and exact description of the invention, such as will enable others skilled in the art to which it appertains to make and use the same.

15 My invention relates to inserts for setting in building material (which fixes the inserts), such as mortar or concrete which is unsuitable for direct insertion thereinto of nails, staples, screws, and other building elements, which however can be firmly fixed by the aid of inserts of the kind indicated.

20 My insert contains improvements which are of considerable value in such articles. It has a metal shell with broad oppositely 25 located flat or curved cheeks and one object of the invention is to space these cheeks apart by a wood or other suitable core or plug, or by indentations or spacing members extending from one (or each) cheek to the 30 other. The spacing members within the insert prevent the cheeks being forced too close together. If they were closer than a suitable minimum and were set in hard concrete it would be impossible to drive common 35 nails between the cheeks. The insert interior is protected from free access of moist matter as mortar or concrete, and it will receive and hold firmly a common nail, screw or various other building elements.

40 The shells are preferably of galvanized iron, and the suitable minimum internal space is a little narrower than the thickness of the nails or building elements to be inserted; the said elements will when being inserted 45 bulge the cheeks outward somewhat, or will groove or aperture them (with or without bulging) according to the resistance by concrete or other external material, and other local conditions.

50 Another object of the invention is to provide for holding inserts so that they can be embedded by flowing concrete and be anchored when the concrete sets. I first tack or nail the insert to a concrete form, and

in some cases also support it otherwise as by 55 a tie wire. Then the concrete is poured, and allowed to set, the form being then removed, any projecting parts of tacks or nails being removed, as by cutting them off. To allow of the said tacking or nailing the inserts 60 have perforated outer lips or flanges.

Another object of this invention is to enable an insert to receive nails or other insertions from a plurality of sides; a plurality of broad receiving mouths or open 65 edges are therefore provided; and an insert with two opposite mouths may for brevity be called a duplex insert. A further object of the invention is to enable concrete when poured to fill a broad space under an insert 70 more satisfactorily than if a broad insert is used in a horizontal position.

Some forms of my construction are shown by drawings herewith but the invention is not limited to these forms nor to any particular 75 designs or minor details of parts.

Figure 1 shows in section a very simple insert in a mortar joint.

Fig. 2 shows in section a duplex insert in a mortar joint. 80

Fig. 3 shows a cross section of Fig. 2.

Fig. 4 is a perspective view of part of an insert, illustrating its mouth and the closed ends of its cheeks.

Fig. 5 shows in section part of a modified 85 insert.

Fig. 6 shows in section a wall having two oppositely set skirting boards fixed to one insert.

Fig. 7 shows in section a wall having two 90 oppositely set architraves and intermediate door framing all fixed to one insert.

Fig. 8 shows in section a curved insert. The scales in these figures differ. The insert in Fig. 2 has (to receive nails or other 95 insertions to be fixed) a mouth at each end, and in Fig. 7 it has three mouths, namely two opposite one another and one connecting the said two.

In these drawings 1 indicates bricks or the like, 2 insert embedding material as mortar or concrete, 3 a concrete form, 4 and 5 skirting boards, 6, 6^a architraves, 7 a door framing, 8 plaster, and 9 nails to attach inserts to concrete forms. 100

A are flat (and N are curved) insert cheeks having lips C, D, spread apart to form insert mouths and having edges or

flanges C¹, D¹, to bear ordinarily on the brick, mortar, or concrete external face. These flanges or edges have holes E when they are to receive nails 9 or the like to attach the inserts to concrete forms 3.

The members which space the cheeks a minimum distance apart are cheek indentations G, or other spacing means are used as a waterproofed or other core B of suitable material as wood, and fixed in position, as by narrowing the insert at F below the insert mouth.

The inserts have keying means comprised by one or more outwardly extending rear enlargements or projections J. Part of the insert to the rear of its mouth has means to receive a support as a wire. Thus L is a hole engaged by a wire M, the upper end (not shown) of the wire being fixed to any 20 convenient support prior to pouring concrete to anchor the insert.

The cheek sides are closed together sufficiently to prevent concrete or mortar freely entering and obstructing the full use of the 25 inserts. Thus the sides are curved together at S, and as a variation one side overlaps the other at Q.

In Fig. 7, Y are fixing nails or the like. I do not show any nail which fixes archi- 30 trave 6^a, but it will be understood that any such nail will enter the insert mouth over which the member 6^a is located. When an insert is to be embedded in concrete in the position seen in Fig. 7 and is broad in 35 plan view, it is desirable to specially promote easy flow of concrete under the insert. The curved cheeks shown in Figs. 7 and 8 assist in promoting suck flow, and the positioning of the rear of the insert higher than 40 the front also so assists. If broad horizontal cheeks were used they would cause voids to occur in the concrete flowing under them.

Having described this invention, what is claimed by Letters Patent is:—

1. An insert of the kind described including a piece of sheet metal bent upon itself to provide a pair of parallel and spaced apart cheeks leaving a substantially continuous space there between of the length and breadth of the cheeks and of narrower width than the thickness of articles to be inserted therein, the metal of one cheek being at a plurality of points pressed through the other cheek and into the space between the cheeks whereby to provide spacing points to prevent the collapse of the cheeks into the space therebetween by the weight of the concrete, a plurality of mouths provided along separate edges of the insert and all leading to the space between said cheeks, flaring jaws at each mouth to guide articles between the cheeks, the edges of the cheeks where the mouths are not formed being bent together and tightly closed to prevent the entrance 65 of concrete or the like, substantially as described.

2. An insert of the character described composed of sheet metal shell bent upon itself to provide a pair of curved cheeks 70 lying close together but substantially parallel throughout and separated by a space slightly smaller than articles to be inserted therein, said cheeks having a flaring mouth along one edge thereof, said mouth being 75 formed to receive fastenings which are adapted to enter a concrete form, whereby the end of the insert remote from the form and innermost with respect to the wall being formed will be in a plane higher than the 80 mouth of the insert to allow the concrete to enter beneath the insert with more facility, substantially as described.

In witness whereof I have hereunto set my hand.

HENRY HUDSON.
